CLAIM

The ornamental design for a portable media playback device, as shown and described.

DESCRIPTION

FIG. 1 is a rear elevation view of a portable media playback device, according to a first embodiment of the invention; FIG. 2 is a front elevation view thereof; FIG. 3 is a top plan view thereof; FIG. 4 is a bottom plan view thereof; FIG. 5 is a first side view thereof; FIG. 6 is a second side view thereof; FIG. 7 is a first perspective view thereof; FIG. 8 is a second perspective view thereof; FIG. 9 is a rear elevation view of a portable media playback device, according to a second embodiment of the invention; FIG. 10 is a front elevation view thereof; FIG. 11 is a top plan view thereof; FIG. 12 is a bottom plan view thereof; FIG. 13 is a first side view thereof; FIG. 14 is a second side view thereof; FIG. 15 is a first perspective view thereof; and, FIG. 16 is a second perspective view thereof. The dashed broken lines in the figures illustrate the portions of the design that form no part of the claimed design.
